York, N. Y., a corporation of Delaware

Application January 13, 1951, Serial No. 205,845

12 Claims. (Cl. 313—32)

1

The present invention relates generally to new and simplified ionic tube structures, capable of handling very high currents, and to novel arrangements for priming, or initiating the discharge of such tubes.

At the present time, a large number of different types of gaseous conduction tubes are known, some of these, specified by way of example, being phanotrons, ignitrons, thyratrons, and excitrons. In addition, polyanodic rectifiers are well known in the art, which operate by means of gaseous conduction. Tubes of the gaseous conduction type, when designed to carry very heavy currents, generally present great difficulties of construction, and of cooling, when arranged in accordance with prior art principles. Thereby, they become complicated and costly. Additionally, relatively complex structure is required for controlling the current passing through the tubes, since this generally involves control of firing times of the tubes.

It is a primary object of the present invention to overcome the above-mentioned difficulties, by providing a simple, economical and readily effectuated construction for gaseous conduction tubes, and a simple and practical method of controlling the firing of such tubes.

More specifically, the construction and operation of gaseous conduction tubes involves several difficulties. If such a tube utilizes an electron emissive cathode, difficulties arise in providing sufficient emission from the cathode, and in disposing of the heat liberated from the cathode. Tubes of the liquid cathode type, on the other hand, involve difficulties of firing initiation, but do not involve difficulty due to limited emission. It is essential, if a gaseous conduction device is to pass a very heavy current, that the cathode provide a very heavy emission. When use is made of liquid cathodes, to provide high emission, an emissive cathodic spot is formed on the surface of the liquid cathode, usually mercury. Use of a mercury cathode provides the advantage of enabling discharge of almost unlimited currents, but involves the serious problem of initiating or forming the cathodic spot precisely at the instant desired, of localizing the cathodic spot, of condensation of mercury vapor on the walls of the tube, of the conductivity of this mercury vapor, of the relatively slow de-ionization time of mercury vapor, and of the formation of ultra-violet rays by the arc. The cathodic spot may be generated either by tilting the tube, or by means of a mobile electrode provided with suitable actuating means. In either case, it is

2

necessary to provide considerable accessory equipment for the tube, for the purpose of priming or forming and maintaining the cathodic spot. It follows that a solution involving mercury cathodes, while acceptable for a polyanodic tube utilizing a single cathode, may be prohibitive if a large number of separate tubes must be utilized in a circuit, and if prior art principles are followed. In the latter case, in fact, the cathodes of the tubes may require to be insulated from one another, and it is usually necessary separately to prime and maintain the cathodic spot in each of the tubes.

It is possible, in accordance with the presently known art, to form and maintain a cathodic spot on a mercury electrode by means of a so-called ignitor electrode immersed in the mercury. However, the apparent simplification which derives from the fact that the ignitor electrode need not be moved, is compensated for by the fact that heavy current must be supplied to the ignitor electrodes, at controlled times, which involves considerable expensive circuitry, and generally in the prior art has involved use of thyratron tubes, condensers, auxiliary control tubes, and phase control devices.

Where oxide coated cathodes are utilized in tubes designed to carry heavy currents, considerable simplification of structure results, since the cathodes may be heated, while electrically isolated, by means of transformers, but the tubes present other difficulties. Specifically, the maximum current which may be passed by the tube is quite limited, because the cathode deteriorates rapidly if too high a current passes for even a very short time. Further, the power consumed in heating the cathode is very considerable, of the order of ten watts per ampere of output. While the latter difficulty may be overcome by heat insulating the cathodes, in which case it is possible to obtain one ampere of discharge in return for one watt of heating current, the latter solution results in considerable time lag in heating the cathode before the tube becomes available for use in a circuit.

A further difficulty which occurs in high power rectifier tubes involves the problem of cooling. An outer water jacket for the tube may be utilized, but this involves a rather delicate design, and requires the insulation of the water conduits. Further, in mercury cathode tubes, in order that the tube shall not fire in reverse direction, it is necessary to prevent condensation of mercury on the anodes of the tubes, and for this purpose the anodes must be maintained at a temperature

higher than the body of the tube. Graphite anodes are normally employed in such tubes, and the cleaning of such anodes, which is necessary after a definite length of service, is a lengthy, complicated and costly affair.

The droplets of mercury which are deposited on the inner walls of the tube interferes with the insulation of the tube, and provides a further difficulty in systems of this type, since it is necessary to maintain the insulators existing between the electrodes, or the structure which provides such insulation in any particular tube structure, at a temperature which is relatively high, to avoid undue condensation of mercury thereon.

Lastly the construction and suspension of control grids in mercury cathode tubes introduces serious difficulty, since the deposit of mercury on the grid can prevent its functioning. Additionally, feeding of control voltages to the grids necessitates auxiliary circuits which are complicated and costly.

It is a primary object of the present invention to provide a monoanodic tube, preferably of the mercury cathode type, which overcomes the above described difficulties.

More specifically, it is an object of the present invention to provide a high powered mercury cathode rectifier tube which may be economically fabricated, and more efficiently cooled than is possible with known constructions.

A further object of the present invention resides in the provision of a mercury cathode high power rectifier which may be readily assembled and dis-assembled.

Still a further object of the invention resides in the provision of a mercury cathode rectifier fabricated of a relatively small number of easily constructed parts.

Another object of the invention resides in the provision of a novel circuit for controlling firing of a tube of the character disclosed, and forming a subject of the present invention.

Still another object of the invention resides in the provision of a mercury cathode tube in which firing may be initiated by means of particularly simple circuits involving no firing tubes.

Another object of the invention resides in the provision of a novel circuit arrangement for connecting the novel tubes of the present invention for rectifying power derived from a three phase source, in controllable amounts, by controlling the firing times of the tubes.

The above and still further features, objects and advantages of the invention will become apparent upon consideration of the following detailed description of a tube structure embodying the invention, and of circuits for controlling firing of one or more tubes constructed and arranged in accordance with the invention, especially when taken in conjunction with the accompanying drawings, wherein:

Figure 1 is a view in longitudinal cross-section of certain elements of a gaseous conduction device, arranged in accordance with the invention, shown separated, prior to their assembly in a completed tube;

Figure 2 is a longitudinal section of a complete and assembled tube, constructed and arranged in accordance with the present invention;

Figure 3 is a schematic circuit diagram of a firing arrangement for a tube arranged in accordance with the invention;

Figure 4 is a schematic circuit diagram of a rectifying system employing six tubes in accordance with the invention, for rectifying power derived from a three phase line; and,

Figure 5 is a schematic circuit diagram of a modification of the system of Figure 4.

Referring now more specifically to the drawings, reference numeral 1 identifies a cup shaped anode, fabricated of thin metal, such as Kovar, or other metal which may be readily de-gassed, and which forms a vacuum tight seal with glass. Anode 1 is sealed, at its upper open edge 2, to a glass annulus 3 which extends radially outward from the anode 1. The outer wall 4 of the tube may be fabricated either of glass or of metal, but in either event is cylindrical, and is provided at its upper edge with an outwardly extending flange 5, formed of glass or the like. The inner diameter of the envelope 4 is greater than the outer diameter of the anode 1, but the flanges 3 and 5 have substantially equal outer diameters, so that the upper surface of the flange 5 may be sealed to the under surface of the annulus 3.

A cathode is provided for the tube, in the form of a metallic cup 6, filled with mercury 7. Resting on the bottom of the cup 6 is a ring 8, which extends above the surface of the mercury 7, and which is provided with apertures 8a, to enable free flow of the mercury beyond the ring 8. The ring 8 serves to localize the cathodic spot on the surface of the mercury 7, when the spot is formed. The metal of which the cup 6 is formed may be Kovar, or other metal suitable for sealing to glass. A glass ring 9 may be sealed to the upper edge of the cup 6, and to the glass ring 9 may be secured a stem 10, having an axial aperture 11 through which the tube may be exhausted, and filled with suitable inert gas, such as xenon, after it has been assembled. Further secured to the glass ring 9 is a glass support 12, through which extends a lead 13, the glass 12 serving as insulation for the lead 13, and the lead 13 terminating in an electrode 14, which may be in the form of an inverted cone, having its apex adjacent to but not touching the surface of the mercury pool 7, axially of the latter. Secured to the under wall of the cup 6 is a further cup 15, having its open end extending downwardly, and about the cup 15 is secured a strap 16, which serves as a cathode lead for the tube. The glass ring 9 may then be secured to the cylindrical envelope 4, of the tube, by sealing if the envelope 4 is of metal, or by welding thereto if the envelope 4 is of glass. The annulus 3 may then be welded to the flange 5 to complete the enclosure for the tube.

The tube formed in the manner above described is of very light structure, and easily fabricated, and the cups and tubes of metal may be readily degassed by high frequency heating, or in other known ways.

Extending co-axially of the anode structure 1 is a metallic tube 20, from the outer wall of which extends a number of metallic cooling fins, as 21, 22. Tube 20 may have substantially the same diameter as the anode 1, although this is not essential, and may be open at its upper end, and there provided with an outwardly bent lip 23, while at its lower end the tube 20 may be provided with an outwardly extending flange 24, extending at right angles to the axis of the tube 20. The flange 24 may be superposed on the flange 3, being separated therefrom by means of a rubber washer or gasket 25, which provides a water tight seal.

Fitting tightly in the lip 23 may be provided a rubber stopper 26, having an axial aperture 27 through which extends a copper tube 28. The upper end of the tube 28 is sealed by means of a

lid 29 through which extends axially, and in sealed relation, a rod 30, which is fabricated of material having a high coefficient of expansion with heat. To provide an easily accessible terminal point, the tube 28 is provided with a circling strap 31, of metal, which firmly contacts the cylinder 28, and which is provided with a radially extending lug 32 to which cable may be readily attached. The tube 28 extends co-axially with the cylinder 20 to a point just within the anode 1. At this point the tube 28 is bent to one side, as at 33 so that it no longer extends co-axially of the tube 20 or of the anode 1, and at at least one point, 34, contacts the inner wall of the anode 1. An extension 35 of the tube 28 is provided, which extends within the anode 1 and co-axially therewith, which is open at its lower end, as at 36, and which is provided with a passage at its upper end as at 37. The rod 30 extends through an opening in the bend 33 of the tube 28, and is in sliding relation thereto, and extends entirely through the tube 35. The rod 30, at its lower end, is provided with a valve 37, which is capable, while the rod 30 is cold, of closing or almost closing the lower end 36 of the tube 35. As the rod 30 heats up, since the rod 30 is fixed at its upper end to the lid or closure 29, the lower end carrying the valve 37 moves downwardly, unmasking the opening 36 of the tube 35. The valve 37, and the rod 30, provide accordingly a thermostatically controlled valve, capable of controlling flow of liquid in extension 35.

The anode 1 and the tube 20 are filled with cooling liquid, which, moreover, fills the tube extension 35, via the opening provided by the valve 37, and fills the tube 28 via apertures 38, which are located just under the stopper 26. When heat is supplied to the cooling fluid, due to passage of current to the anode 1, the cooling fluid passes upwardly by convection, as indicated by the arrows 39, 40, within the tube 28, passes through the openings 38 and then downwardly between the inner wall of the cylinder 20 and the outer wall of the tube 28, through the interior of the tube extension 35, as indicated by the arrows 40, and out through the space between the lower edge 36 of the tube 35 and the valve 37, as indicated by the arrows 41.

In order to assure contact between the tube 35 and the anode 1 there is provided at least one fixed spring, as 42, which radiates from the tube 35 to the inner walls of the anode 1 in the form of a spiral. Thereby firm contact is made between the anode 1 and the tube 28, and hence the terminal lug 32.

In order to provide cooling of the wall 4 of the tube there is provided an encircling metal cylinder 45, having a greater diameter internally than does the wall 4 externally, so that a space for cooling liquid is provided therebetween. The encircling cylinder 45 is provided at its upper end with inwardly extending flange 46, designed to be secured to the underside of the flange 5 of the wall 4, and being separated therefrom by means of a rubber gasket 47, which provides a water tight seal. The lower edge of the encircling cylinder 45 flares outwardly, as at 48, and a sealing ring 49 of trapezoidal cross section is wedged into the space between the outwardly flaring rim 48, and the ring 9, by means of a metal ring 50 located under the sealing ring 49. Pressure is exerted between the flange 24 of the cylinder 20 and the metal ring 50 by means of a plurality of draw bolts, as 51, which may be tightened by wing

nuts as 52, and when tightened, the draw bolts 51 effectively seal the gasket 25, the gasket 47 and the ring 49, thereby securing as one unit the various components of the tube structure. Cooling liquid may be supplied internally of the encircling cylinder 45 by means of an aperture 53 provided therein, and the liquid, after having absorbed heat from the wall 4, may be withdrawn via a further aperture 54 in the encircling cylinder 45.

Reference is now made particularly to Figure 3 of the accompanying drawings wherein is illustrated a schematic circuit diagram of an arrangement utilized for initiating a cathodic spot on the mercury cathode 7 of the tube illustrated in Figure 2 of the accompanying drawings.

In the schematic circuit diagram of Figure 3 of the accompanying drawings is shown a condenser 60, in series with an inductance 61, the junction point between the condenser 60 and the inductance 61 being designated 62, and the free end 63 of the condenser 60 being connected via lead 64 to the cathode 7, while the free terminal 65 of the inductance 61 is connected via lead 66 to the control electrode 14. Between the terminal 62 and the terminal 65 are connected in series a condenser 67, secondary winding 68 of an induction coil 69, and a spark gap 70. The primary winding 71 of the induction coil 69 is connected in series with a source of current 72, designated as a battery for purposes of convenience, and with a pair of breaker points 73. Accordingly, when the breaker points 73 are closed current flows in the primary winding 71, and when the breaker points 73 are opened rapidly, current flow in the primary winding 71 is interrupted, resulting in the induction of a high voltage in the secondary winding 68. The voltage induced in the secondary winding 68 is sufficiently great to result in formation of a spark in the spark gap 70, causing a sudden flow of current in the inductance 61, and thereby generates a high voltage between the control electrode 14 and the cathode 7, resulting in an ionization of the rarified gas which is provided in the interior of the tube. This rarified gas may be a gas such as xenon, and additionally, there may be present in the tube mercury vapor arising from the cathode 7. The spark which occurs between the control electrode 14 and the cathode 7 is said to pilot the priming of the arc in the tube, or to initiate its formation, and by suitably timing the opening of the breaker points 73 with respect to the phase of a voltage which may be applied to the anode of the tube, the time of current flow through the tube may be controlled.

While a spark is generated between the control electrode 14 and the cathode 7, the tube cannot be fired by this spark alone, due to the relatively small current which exists in this spark. To supplement the current due to spark formation, the condenser 60, which may be of considerable size, is charged heavily through a resistance 75 and a secondary winding 76 of a transformer 77, having a primary winding 78. The condenser 60 is accordingly charged with alternating current. However, the phase of this alternating current may be so arranged that the terminal 62 is highly positive at the time when the spark is caused to pass between the control electrode 14 and the cathode 7. The passage of this spark completes a circuit for the condenser 60, or provides a low impedance discharge path therefor, and the condenser accordingly discharges, via the inductance 61, providing sufficiently heavy current to vola-

tilize the mercury of the cathode 7, and sufficient ionization to fire the tube, i. e., to effect passage of current from the anode to the cathode of the tube, provided the anode is positive.

In order that the direction and magnitude of the charge in the condenser 60 may be suitable, at the time when the breaker points 73 are opened, the breaker points 73 may be actuated by an electromagnet 80, energized from alternating current supply terminals 81, and the primary winding 78 of the transformer 77 may be supplied with voltage from the same terminals 81, the circuit constants and delay times of the mechanical breaker points 73 being properly selected.

The condenser 67 is not essential if only a single tube is to be controlled, but may become necessary to provide D.-C. blocking in a system utilizing a plurality of tubes. The condenser identified by the reference numeral 92 may represent the inherent capacity of the secondary winding 68 of the transformer 69, but in some cases it may be desirable to supplement this inherent capacity by an additional condenser, to raise the total voltage developed across the secondary winding 68.

Reference is now made to Figure 4 of the accompanying drawings, which provides a schematic circuit diagram of a rectifying system employing three pairs of tubes connected in known fashion to a three phase line, to supply rectified current to a load circuit. The tubes utilized in the system of Figure 4 may correspond with the structure which is illustrated in Figure 2 of the accompanying drawings, and while the generation of priming current for the control electrodes of the tubes employ the principles of the circuit illustrated in Figure 3 of the accompanying drawings, it is found preferable to eliminate mechanically actuated breaker points, and to substitute purely electrical devices for generating the necessary pilot sparks between the control electrodes and the cathodes of the tubes.

In the system of Figure 4 the reference numeral 100 represents a three phase line, and the reference numeral 101 represents a load circuit to which rectified current is to be supplied from the three phase line 100. Three gaseous conduction devices 102, 103 and 104 are connected with their anodes to the separate phases of the three phase line, their cathodes being connected together to a lead 105, which represents then the positive D.-C. terminal of the system, and which may be connected accordingly to the positive terminal of the load 101. If the separate lines of the three phase line 100 be identified by the reference letters A, B and C, the tubes 102, 103 and 104 may have their anodes connected to the lines A, B and C respectively. A further gaseous conduction device 106 may have its cathode connected to the line C, a gaseous conduction device 107 may have its cathode connected to the line B, and a gaseous conduction device 108 may have its cathode connected to the line A. The anodes of the gaseous conduction devices 106, 107, 108 are connected together by means of a lead 109, which then forms the negative terminal of the rectifying system, and may be connected to the negative terminal of the load 101. It follows that, as between pairs of lines of the three phase source 100 are connected pairs of tubes in series with the load. Since the separate lines A, B and C reach their maximum voltage values in a positive direction at time separations equal to 120° of the source frequency, the tube pairs conduct

in sequence at 120° time intervals, resulting in a fairly steady current in the load 101.

The mode of connection of the gaseous conduction devices to the three phase line and to the load is conventional per se. The present invention resides in the system employed for effecting controlled firing of the tubes.

In order to effect controlled firing of the gaseous conduction devices, 102-104, 106-108, periodic voltage impulses are generated, by means of a device 110, at 120° intervals as measured by the frequency of the three phase line. These voltage impulses, further, may be delayed or advanced in phase, with respect to the phase of the source, and the times of occurrence of these voltage impulses determines the times of firing of the gaseous conduction devices, 102, 103, 104, 106, 107, 108.

The device 110 comprises a thyratron tube 111, having an anode 112, a control electrode 113 and a cathode 114. Voltage is supplied to the anode 112 through a rectifier 115, supplied from all three phases A, B and C and of source 100 simultaneously, the rectifier 115 feeding the anode 112 via a resistance 116. The cathode 114 of the thyratron 111 is connected back to the three phase line via three rectifiers 117, poled oppositely to the rectifiers 115, to enable current flow from the three phase line through the rectifier 115 through the resistance 116, the thyratron 111 and from anode 112 to cathode 114, and back to the three phase line via the rectifier 117.

Connected between anode 112 and cathode 114 of thyratron 111, is a primary winding 118 of a transformer 119, in series with a condenser 120. Bias voltage for the control electrode 113 of the thyratron 111 is supplied via a conventional rectifier system 121, which derives power from one phase of the three phase line 100, and which supplies voltage across an output resistance 122. The control electrode 113 is connected via an adjustable tap 123 to the resistance 122, so that the total D.-C. bias voltage on the control electrode 113 may be selectively varied. In series between the control electrode 113 and the tap 123 is the secondary winding 124 of a transformer 125, and a voltage limiting resistance 126. The primary winding 127 of the transformer 125 is connected between the cathode 114 and the output terminal of the rectifier 115, via a condenser 128, and to the low voltage terminal of the resistance 116, via a further condenser 129.

Since the voltage occurring at each end of the resistance 116 is not filtered, it contains pulsations at six times the frequency of the three phase line 100 and these pulsations are transferred to the control electrode 113, in series with the D.-C. bias impressed thereon from the resistance 122 forming the output load of the rectifier 121. The times of these pulsations determine then times when the potential of control electrode 113 of the thyratron 111 becomes more positive than normal, and thus define firing times for the thyratron 111.

In operation, the condenser 120 is charged via the rectifiers 115 and 117, the thyratron 111 being maintained non-conductive by the bias rectifier 121, and the charging time of the condenser 120 via the resistance 116 is so set that the condenser contains a very considerable charge at the time when a pulsation is applied to the control electrode 113 to render the thyratron 111 conductive. At this instant the condenser 120 discharges through the thyratron,

providing a sharp pulse of current in the primary winding 118 of the transformer 119. Thereby a high voltage pulse is generated in the secondary winding 130 of the transformer 119. The high voltage pulses generated in the secondary winding 130 occur six times during each cycle of voltage in the three phase line 100, at 120° phase intervals, and determine the firing times of the gaseous conduction devices 102, 103, 104, 106, 107, 108. These firing times may be varied by adjusting the bias on the control electrode 113, by varying the position of the slider 123, in accordance with principles which are well known per se.

The voltage pulses available across the secondary winding 130 of the transformer 119 are applied between two leads or bus-bars 131 and 132. Directly connected to the bus-bar 131 are six spark terminals 133, 134, 135, 136, 137 and 138, which, as will appear hereinafter, are allocated respectively to the gaseous conduction devices 102, 103, 104, 107, 108. Similar spark gap terminals 139, 140, 141, 142, 143 and 144 are connected to the bus 132, but via primary windings 145, 146, 147, 148, 149 and 150, respectively. Accordingly, the voltage supplied by the secondary winding 130 is applied simultaneously and in identical phase to each pair of opposed spark gaps, as 133, 139, or 134, 140, etc. It is desired, however, that these spark gaps break down in time sequence, at 120° time intervals, since the spark gaps control the gaseous conduction devices respectively, and since, therefore, each spark gap must break down at the proper time to accomplish firing of the proper one of the gaseous conduction devices.

In order to accomplish controlled break down of the spark gaps there is provided intermediate each pair of spark gap terminals as 133, 139 or 134, 140, etc., a metallic ring, these rings being identified, respectively, by the reference numerals 151, 152, 153, 154, 155, 156. The voltage applied between any spark gap terminal pair, as 133, 139, or 134, 140, etc., and the spacing of the terminal pairs, is such that the gaps will not break down unless the associated ring is at a suitable potential for this purpose. The function of these rings is to modify the voltage gradient existing between any terminal pair in such way that break-down may occur. To this end there are applied to the rings 151 to 156, inclusive, voltages from a transformer 160, which is energized from the three phase line 100, and which applies to the rings voltages separated by 120°. Break-down can occur only while a ring has a voltage adjacent to a maximum value, as available from the transformer 160.

Accordingly, the transformer 160 applies voltages to the rings 151—156, in sequence, which controls the sequence of break-down of the spark gaps. The actual timing of each breakdown is, however, in response to an impulse provided by the secondary winding 130, so that the actual timing of the break-down may be controlled over a considerable range of values, by adjustment of the slider 123.

When any spark gap breaks down the associated primary winding of transformers 145 to 150, inclusive, conduct current. Thereby voltages are induced in the corresponding secondary windings, which are applied between cathode and control electrode of the associated gaseous conduction devices. The spark gap devices accordingly perform the same function in the system of Figure 4 as does the mechanically operated

circuit maker and breaker device utilized in the system of Figure 3. It will be clear, therefore, that in the system of Figure 4 a mechanically operated spark generator may be utilized in place of the spark generator disclosed. This is, however, undesirable, and the system of Figure 4 being preferable, because no moving parts are involved in the latter, the system being entirely electrostatically controlled.

The spark discharges provided by the transformers 145 to 150, inclusive, are not sufficient, however, of themselves, to effect firing of the gaseous conduction devices 102, 103, 104, 106, 107, 108, but each serves merely to provide a discharge path for a condenser, which discharges a heavy current between the control electrode and cathode of the gaseous conduction device, and it is the condenser discharge which actually accomplishes firing of the tubes.

In order to provide a condenser discharge between control electrode and cathode of each of the gaseous conduction devices of the present system, there are provided six condensers 161 to 166, inclusive, each of which is connected in series with a resistance, as 167 to 172, inclusive, and each condenser and associated resistance, as 161, 167, or 162, 168, etc., is connected across one output phase of a transformer 175 which is energized from the three phase line 100, and which supplies, across six separate output or secondary windings, voltages separated by 120°. Accordingly, the condensers 161 to 166, inclusive, are being continually supplied with alternating current voltage from the transformer 175, but at 120° separation of phase in the separate condensers.

Each one of the condensers, as 161 to 166, inclusive, is connected through a secondary winding of one of the transformers 145 to 150, inclusive, between control electrode and cathode of one of the ionic discharge devices, as 102 to 104, 106 to 108. For example, a circuit may be traced from condenser 161 through the secondary winding of transformer 145, via lead 176, to the control electrode of gaseous conduction device 102, and from the cathode of that device back via lead 177 to the other side of the condenser 161. While the voltages available across the condensers are continuously being applied between control electrodes and cathodes of the gaseous conduction devices, their magnitudes are so selected that the gaseous conduction devices do not fire in response thereto. When, however, a pilot spark is caused to occur in any gaseous conduction device, a low impedance path is thereby provided between control electrode and cathode of the associated tube, and thereby a low impedance discharge path for the associated condenser. It follows that the condensers discharge only in response to the pilot sparks. The pilot sparks are so timed, and the condensers are so driven, that at the time a pilot spark occurs considerable voltage exists across the associated condenser, so that a very heavy current discharge then appears in the gaseous conduction device. Firing occurs, in response to that heavy current. Once firing has been initiated the anode to cathode voltage of the tube maintains the arc, and current flows to the load 101.

Reference is now made to the system of Figure 5, which represents a modification of the system of Figure 4, which, because of the mode of connection of the rectifying gaseous conduction devices in the system, permits use of a simpler firing control arrangement than is possible in

Figure 4. Specifically, in the system of Figure 5 the cathodes of all the gaseous conduction devices are at a common potential and inter-connected, which eliminates the need for circuit isolation, as provided by the transformers 145 to 150, inclusive, of the system of Figure 4.

Referring now more specifically to the system of Figure 5, the three phase line 100 supplies energy to a transformer 200, which is so arranged that its six windings provide voltages 120° out of phase at the frequency of the three phase source. The common point of the windings 200 is connected to the negative terminal of load 101, and the remaining terminals of the windings of the transformer 200 are connected to the anodes, respectively, of the gaseous conduction devices 102, 103, 104, 106, 107, 108. The cathodes of the gaseous conduction devices are connected together and to the positive terminal of the load 101. The arrangement of the transformer 200 and the associated gaseous conduction devices is, per se, well known, and forms no part of the present invention, which is, on the contrary, directed to the firing control system for the tubes.

In accordance with the system of Figure 5 there is provided a pulse generator 110, which corresponds with the pulse generator 110 illustrated schematically in Figure 4 of the drawings. As in the system of Figure 4 a transformer 160 supplies 120° phase separated voltages to rings 151 to 156 inclusive, which control the order in which the spark gap pairs, as 133, 139 or 134, 140, etc. break down. Voltage pulses from the source 118 are applied in common to bus 131 and thence to spark terminals 133 to 138, inclusive. The remaining terminal of the voltage pulse source 110 is applied to a corresponding terminal of each of the condensers 202, 203, 204, 205, 206 and 207. The remaining terminals of these condensers are connected, respectively, to one terminal of each of windings 208, 209, 210, 211, 212 and 213. The remaining terminals of these windings are connected, respectively, to the remaining spark gap terminals 139 to 144.

Accordingly, when any spark gap pair breaks down current flows through the associated condenser and coil. For example, should the spark gap pair 133 to 139 break down a circuit will be completed from common bus 131 to terminal 139, coil 208, condenser 207, common line 201, back to the voltage pulse generator 110.

Accordingly, break-down of any spark gap pair is accompanied by current flow in the associated coil, and therefore by the generation of a relatively high voltage across the coil. The voltage available across each of the coils 208 to 213, inclusive, is applied via one of condensers 202 to 207, respectively, between control electrode and cathode of the gaseous conduction devices 102, 103, 104, 106, 107, 108, respectively. Thereby each passage of a spark gap between one of the spark gap terminals pairs, as 133, 139, or 134, 140, etc., results in creation of a pilot spark in the associated one of the gaseous conduction devices, as 102, 103, etc.

The condensers 202, to 207, respectively, are charged with alternating current, by means of the transformer 175, and the phase of the current in the separate condensers are separated by 120°. The timing of condenser charging is so arranged that at the time a current flow from one of the coils 208-213, respectively, passes through the associated condenser, a considerable voltage exists across that condenser, deriving

from the transformer 175. Passage of the pilot spark in the gaseous conduction device provides a low impedance discharge path in the device for the condenser, which accordingly discharges, in series with the coil. Tracing through the discharge path for the condenser, 202, taken by way of example, it will be clear that this condenser may discharge over lead 202, through winding 213, from control electrode to cathode of gaseous conduction device 108, and back to the other side of the condenser 202.

Accordingly, whenever a pilot spark is generated in one of the gaseous conduction devices 102 to 104, 106 to 108, it is accompanied by discharge of a condenser, so that a heavy transient current flows between control electrode and cathode, resulting in firing of the tube.

In summary, it will be clear that I have provided a novel gaseous conduction device, which may be very readily fabricated, which possesses a relatively low internal volume so that it may be readily evacuated, and that the cooling facilities for the tube may be readily disassociated from the tube proper, whereby if the latter burns out a considerable portion of the equipment may be salvaged. Furthermore, anode cooling and envelope cooling are accomplished by separate fluid flows, so that the envelope itself may be maintained at a sufficiently high temperature to assure that mercury droplets will not collect thereon, while the anode itself may be cooled to any convenient and desired temperature, which may be automatically controlled by structure inherent in the cooling system.

The specific tubes disclosed may be utilized in novel circuits, as illustrated in Figures 3 to 5, inclusive, and may be fired by arrangements which do not include movable electrodes or firing tubes, as is common in the prior art, and which are controlled electrostatically and without the expenditure of large amounts of energy. Two specific arrangements are shown for rectifying current deriving from a three phase line. At the same time, in accordance with principles well understood in the art, by proper timing of the firing of the tubes, the voltage provided by the three phase line may be changed in frequency, instead of being rectified, and other important functions in the art may be accomplished by employing tube firing systems arranged in accordance with the basic concepts of the present invention.

While I have described and illustrated specific forms of the invention it will be clear that variations thereof may be resorted to without departing from the true scope of the invention as defined in the appended claims.

What I claim and desire to secure by Letters Patent of the United States is:

1. A gaseous conduction device, comprising, a cathode, an anode, a container for supporting said cathode and anode, said container comprising two separable parts respectively supporting said anode and said cathode, each of said parts having an externally extending glass flange for sealing the parts to one another, said anode consisting of a hollow receptacle extending internally of said container, said receptacle filled with cooling liquid.

2. The gaseous conduction device of claim 1 wherein said separable parts are nested one within the other, said cathode comprising an electrically conducting cup containing mercury, said cup having a rim sealed to the lower of said nested parts, a rod of insulating material secured

to said lower part and extending over said mercury, a control electrode, a lead extending through and beyond said rod of insulating material, said control electrode secured to and supported by said lead adjacent its point of extension beyond said rod of insulating material.

3. A gaseous conduction device, comprising, a tube of insulating material having a lower edge and an upper edge, a hollow cylindrical anode having a closed bottom and an open top, a first flange of insulating material for suspending said open top in insulated and sealed relation from said upper edge, a hollow cylindrical cathode container having an open top defined by an upper rim and having a closed bottom, a quantity of mercury in said cathode container, a second flange of insulating material for suspending said upper rim of said cathode container from said lower edge of said tube in sealed relation.

4. The combination in accordance with claim 3 wherein is further provided means for supplying a flow of cooling liquid to and from internally of said hollow cylindrical anode.

5. A gaseous conduction device comprising, a ring of insulating material, a hollow cylindrical cathode container having an open top defined by an upper edge and having a closed bottom, means for sealedly securing said upper edge in said ring, a tube having an upper edge and a lower edge, means for sealing said lower edge of said tube to said ring, a hollow cylindrical anode having an open top defined by an edge and a closed bottom, and means for insulatedly and sealedly securing said edge of said anode to said upper edge of said tube, whereby said anode extends internally of said tube.

6. A gaseous conduction device, comprising, a container having internally thereof an anode, a cathode and a control electrode, a cooling system for said container comprising a cooling structure and anode lead, means for detachably securing said cooling structure and anode lead to said container, said anode comprising a concave structure extending internally of said container, said anode lead contacting said anode and comprising a pipe structure for conveying cooling fluid to and from said anode.

7. A gaseous conduction device comprising a first container portion having a first flange, a hollow receptacle anode supported by said first container portion, a second container portion having a second flange, a cathode supported by said second container portion, said first and second flanges being of substantially the same diameter and being removably sealed to one another, cooling liquid within said hollow anode,

and control means within said hollow anode for varying the flow of said liquid.

8. The device of claim 7 in which said control device comprises a tube extending into said liquid within said hollow anode, a rod having a variable temperature coefficient within said tube, and a valve device fixed to the end of said rod adjacent one end of said tube.

9. A gaseous conduction device comprising a first portion having a cylindrical receptacle anode sealed at its upper edge to a first flange of insulating material, a second portion comprising a cylindrical wall of insulating material coaxial with said anode and supporting a mercury pool cathode coaxially with said anode, said cylindrical wall having a second flange of insulating material at its upper edge adapted to be sealed to said first flange.

10. The device of claim 9 including a first cooling mechanism removably clamped to said device said first cooling device comprising a cylindrical member above said anode, cooling liquid within said cylindrical member and the outer surface of said anode, a tube extending from said cylindrical member into the hollow of said anode, a rod within said tube extending within the hollow of said anode and affixed to one end of said tube, and valve means fastened to said rod adjacent the other end of said tube.

11. The device of claim 10 in which said tube defines openings adjacent its upper end, said cooling liquid passing by convection through the openings in said tube, said valve means defining a variable opening at the lower end of said tube to control the flow of liquid therethrough.

12. The device of claim 9 including a first cooling mechanism above said first portion and extending into said cylindrical anode, and a second cooling mechanism surrounding said cylindrical wall.

PIERRE M. G. TOULON.
